UNITED STATES PATENT OFFICE

SIDNEY G. PLUMMER, OF OAKLAND, CALIFORNIA

PONTOON

Application filed December 10, 1929. Serial No. 413,052.

The invention relates to pontoons for supporting pipe lines or other structures over water.

An object of the invention is to provide a 5 pontoon comprising separable and pre-formed sections completely cooperative to provide a float element, said sections being arranged for mutual nesting into a particularly compact relation for the transportation 10 thereof.

Another object of the invention is to provide a particularly simple means for releasably securing the pontoon sections in operative assembly.

15 A further object of the invention is to provide for the complete disposal of the aforesaid securing means within the confines of the pontoon.

Yet another object is to provide a pontoon 20 of the class described which provides a completely water-tight compartment.

The invention possesses other objects and features of advantage, some of which, with the foregoing, will be set forth in the following 25 description of a preferred embodiment of the invention which is illustrated in the accompanying drawings, in which:

Figure 1 is a plan view of a pontoon embodying the invention.

30 Figure 2 is a fragmentary longitudinal section of the pontoon at 2-2 in Figure 1.

Figure 3 is an enlarged view of a portion of the showing of Figure 2.

Figure 4 is an enlarged fragmentary section 35 at 4-4 in Figure 2.

Figure 5 is a plan view showing a pair of the pontoons arranged as a float for a pipe of a pipe line.

Figure 6 is a partly sectional elevation at 40 6-6 in Figure 5.

Figure 7 is a longitudinal sectional view showing the sections of a number of pontoons nested for shipment.

As particularly illustrated, the present invention is embodied in the structure of a 45 pontoon 8, the details of which are particularly brought out in Figures 1 to 4 inclusive. In its disclosed form, the pontoon is seen to comprise an elongated hollow shell of circular cross-section tapering from its central

portion to closed and more or less rounded head portions 9 whereby the pontoon sections 11 and 12 defined at opposite sides of the pontoon center are each of generally frusto-conical outline and the pontoon is generally 55 fusiform. The pontoon is divided at the said center thereof whereby the said sections 11 and 12 are arranged to be preformed as separate elements. The sections 11 and 12 are preferably formed of metal plate with 60 the head and side portions integrally related, as is particularly shown in Figure 2.

Preferably, and as shown, the two sections 11 and 12 are of like outline, and said sections, by reason of their taper, are arranged 65 for nesting with corresponding parts of adjacent nested sections in juxtaposition, the relation being particularly brought out in Figure 7. In this manner, a plurality of the sections is arranged for mutual nesting 70 whereby the sections of several pontoons are arranged to be nested within the space occupied by a single assembled pontoon. The provision of the latter feature is the primary 75 purpose of the present invention, for it appreciably reduces transportation costs for the pontoons and at the same time permits a factory-preforming of the sections for an assembly of the pairs of sections to form the pontoons at the point of use thereof.

Means are provided for detachably securing a pair of sections 11 and 12 together in 80 mutually sealed and coaxial relation to provide a liquid-tight float, the aforesaid means including an annular ring 13. Annular 85 grooves 14 are provided in the axially opposite faces of the annulus 13 for the reception of the free edges 15 of the sections, it being noted that said edges lack flanges and are imperforate. Packing rings 16 of resilient 90 and water resistant material are engaged in the grooves 14, and said grooves are somewhat wider than the edges 15 whereby a pressing engagement of the edges against the rings axially of the annulus 13 permits 95 a lateral spreading of the ring material to somewhat embed the edges 15 therein and insure a seal therat. Preferably, and as shown, the groove sides are angularly related 100 to the plane of the annulus whereby the

grooves are widest at their mouths; in this manner, a centering reception and engagement of the section edges in the grooves is provided for. The rings 16 are preferably arranged to originally be of circular section, and are shown in uncompressed condition in Figure 3.

For securing the two sections in the aforesaid sealed relation with the annulus 13, a 10 tension rod or bar 16 is utilized, said rod being operative between the sections axially thereof for simultaneously urging a sealed engagement of the section edges 15 in the grooves 14. As shown, the bar 16 is formed 15 with like sections 17 connected by means of a turnbuckle 18 and is detachably fixed at its extremities to the different section heads. As shown, diametrically disposed webs 19 are provided within the section heads 9, 20 said webs being integrally secured to the heads and being coplanar with the pontoon axis. The webs 19 are perforated adjacent their free edges to receive bolts 21 of clevises 22 carried at the rod extremities in threaded 25 engagement therewith.

To permit access to the interior of the pontoon for installing, tightening or loosening the rod 16, one pontoon section is provided with a manhole 23 in the side thereof; 30 as shown, the sections 12 are provided with the manholes, said sections being otherwise the same as the sections 11. Preferably, the opening at the manhole 23 is unflanged whereby interference with the nesting of the 35 sections is avoided. A suitable cover 24 is provided for removable mounting at the manhole 23.

The aforesaid arrangement by which the rod 16 is disposed and concealed within the 40 pontoon cavity is seen to provide a pontoon having a smooth exterior. Furthermore, the cooperative assembly of the pontoon sections is controlled entirely by the one rod 16 whereby assembly or disassembly of the pontoon 45 may be quickly and readily effected. The present structure is thus seen to constitute a true knock-down pontoon which may be assembled without requiring skilled labor, the cooperative use of the tension rod 16 and 50 annulus 13 replacing riveting or bolting as a means for securing the sections together whereby no perforating of the section sides at the edges 15 is required, and the sections are of particularly simple structure. A further 55 advantage of the present structure is seen to lie in the fact that the edges 15 of the opposed pontoon sections need not be of exactly equal diameter, thus eliminating any requirement for an exact fitting of the sections to each other, as would be required for riveting or bolting said edges together.

It will now be noted that the present pontoons are particularly intended for use in floating a dredger pipe line or the like. A 65 typical use of the pontoons is disclosed in

Figures 5 and 6, wherein a pair of the pontoons 8 is shown fixed together and in parallel spaced relation by means of a pair of yoke rods 26 connected to and between corresponding ends of the pontoons, and provide a 70 float for horizontally supporting a pipe length 27 of a pipe line 28. In the present instance, the pipe length 27 is fixed transversely across each pontoon at its center by means of a pair of U-bolts 29 engaging the 75 pontoon in their loops and at opposite sides of the pipe. The bolt ends 31 extend upwardly for engagement through clamp plate members 32 disposed transversely across the pipe. Suitable pillow blocks 33 are interposed between the pontoon and pipe to hold the same spaced and against relative angular movement, and nuts 34 engage the extremities of the upper bolt ends for releasably clamping the pontoon 8, pipe 27, members 32, and 80 blocks 33 together in a unitary assembly.

From the foregoing description taken in connection with the accompanying drawings, the advantages of the construction and method of operation will be readily understood by 85 those skilled in the art to which the invention appertains, and while I have described the principle of operation, together with the device which I now consider to be the best embodiment thereof, I desire to have it understood that the device shown is merely illustrative, and that such changes may be made, when desired, as fall within the scope of the appended claims.

Having thus described my invention, I 100 claim as new and desire to secure by Letters Patent of the United States the following:

1. A pontoon comprising a shell intermediate divided solely transversely thereof to provide a pair of axially-separable sections 105 of frusto-conical and similar outline for mutually nested engagement.

2. A pontoon comprising a generally fusiform shell divided to provide separable sections of like outline for mutually nested engagement with each other and with the sections of other pontoons of like structure in a single assembly.

3. In a pontoon, a shell providing a single sealed cavity and divided to provide separable sections, and means operative entirely within the said cavity of the pontoon to releasably secure the said sections in cooperative relation.

4. In a pontoon, a shell divided to provide separable sections, tension means operative between the sections and entirely within the cavity of the pontoon to releasably secure the said sections in cooperative relation, and sealing means at the junction of the said sections.

5. In a pontoon, a shell divided to provide mutually sealed separable sections, tension means operative entirely within the cavity of the pontoon to releasably secure the said

sections in cooperative relation, a said section being provided with an opening affording access to said tension means, and a member removably mounted at said opening to seal the same.

5 6. In a pontoon, a fusiform shell intermediately divided transversely of the axis thereof to provide axially-separable sections, a separate element interposed between opposed edge portions of the said sections and providing channels for the reception of said edge portions, resilient packing in said channels and compressedly engaged between said edges and element, and a tension member of
10 adjustable length cooperative with and between said sections to releasably fix the same in mutually sealed engagement with said element with an adjusted degree of pressure.

In testimony whereof, I affix my signature.

20 SIDNEY G. PLUMMER.
